ATTORNEY

UNITED STATES PATENT OFFICE.

HENRY CAVE, OF HARTFORD, CONNECTICUT, ASSIGNOR TO THE FULLER BRUSH COMPANY, OF HARTFORD, CONNECTICUT, A CORPORATION OF CONNECTICUT.

BROOM.

Application filed August 31, 1925. Serial No. 53,541.

My invention relates more especially to that class of cleaning implements above named, and an object of my invention, among others, is the production of a broom that shall be durable, particularly efficient for the purposes for which it is employed, and one embodying simplicity in construction whereby it may be produced at a minimum cost.

10 One form of broom embodying my invention and in the construction and use of which the objects herein set out, as well as others, may be attained, is illustrated in the accompanying drawings, in which—

15 Figure 1 is a side view of a broom embodying my invention with the handle broken off.

Figure 2 is an end view of the same.

Figure 3 is a side view of the broom body.

20 Figure 4 is a view similar to Figure 1, but showing a slightly different form of construction.

Figure 5 is a plan and edge view of the fiber retaining band shown in Fig. 4.

25 Figure 6 is a side view of the upper portion of the broom body showing this latter form of construction.

In the accompanying drawings the numeral 7 indicates the handle of my improved broom that may be of any suitable material and of any usual shape, this handle projecting into a handle socket in one end of a metal head 8. This head is preferably formed from sheet metal in any suitable manner, as by stamping or drawing, and it preferably gradually widens from the handle socket to the mouth in which the end of the broom body is received.

30 The ends 10 of the fibers are closely compacted and associated as by means of a holding or retaining band 12 encircled about the ends of the fibers to firmly secure them. Stitching 13 may be employed, if desired, at a suitable distance from the end of the body to retain the fibers in place.

40 The inner end of the body is inserted within the socket in the metal head 8 and is forced firmly into said socket, and rivets 14 are then inserted and driven or otherwise passed through the metal head and the broom body, these rivets being located alternately 45 on opposite sides of the band 12, the rivets

and band being so disposed or shaped that the rivets or band will have a staggered arrangement. This causes the retaining band to be indented into the mass of fibers and 50 broom body to be thereby securely held within the socket in the metal broom head and against movement in all directions. In the form of the structure shown in Figures 1, 2 and 3 the holding or retaining band is 55 straight and the rivets have a staggered relation, being located alternately on opposite sides.

In that form of the device illustrated in Figures 4, 5 and 6, the structure is substantially the same as that hereinabove described with the exception that the retaining band is of a little different form from that hereinbefore referred to. This retaining band 15 is sinuously formed, the bends being 60 preferably of angular shape and regularly located lengthwise of the band. The bends on opposite sides of the band are reversely positioned so that when viewed in edge view, as in Figure 5, openings 16 are formed. In 65 this form of construction the rivets 17 are located in a straight line, but when so located they are projected through the openings 16, or in other words, a single rivet will be located in the bend on one side of the 70 band on one side of the metal head and in the bend on the opposite side of the band on the opposite side of the metal head.

In accordance with the provisions of the patent statutes I have described the principles of operation of my invention together with the device which I now consider to represent the best embodiment thereof; but I desire to have it understood that the device shown is only illustrative, and 85 that the invention may be carried out by other means and applied to uses other than those above set out and within the scope of 90 the appended claims.

I claim—

95 1. A broom including a broom body formed of strands closely associated and compacted at one end, a holding band encircling said strands near the end of the broom body, a head encircling the end of 100 said broom body, and rivets extending through said head and said broom body,

said rivets and holding band being arranged to dispose part of the rivets above and the rest of the rivets below said band.

2. A broom including a broom body formed of strands closely associated and compacted at one end, a holding band encircling said strands near the end of the

broom body, a head encircling the end of said broom body, and rivets extending through said head and said broom body, said band being bent to locate it above and below said rivets. 10

HENRY CAVE.
